We claim the ornamental design for a bottle, as shown and described.

DESCRIPTION

FIG. 1 is a bottom perspective view of a bottle showing our new design;

FIG. 2 is a front view thereof, the right side view, left side view and rear view being identical thereto;

FIG. 3 is a top view thereof;

FIG. 4 is a bottom view thereof;

FIG. 5 is identical to the lower half of FIG. 2 and is provided solely for the purpose of defining the sectional view shown in FIGS. 6; and,

FIG. 6 is a sectional view thereof, taken along line 6-6 of FIG. 5.

The broken lines shown in FIGS. 1 through 6 represent environmental subject matter and form no part of the claimed design. The dash-dot line appearing in FIGS. 2 through 4 represents an unclaimed border between claimed and unclaimed subject matter and forms no part of the claimed design. In FIGS. 1 and 2, the bottle is shown with a symbolic break in its length. The appearance of any portion of the bottle between the break lines forms no part of the claimed design. Lines representing claimed and unclaimed subject matter that are visible through the transparent material of the claimed design are omitted from FIG. 1.
